A. B. Leapham
Attorney.

UNITED STATES PATENT OFFICE.

GEORGE A. MOORE, OF MEDFORD, MASSACHUSETTS.

EMBROIDERY-HOOP.

1,244,230.

Specification of Letters Patent. Patented Oct. 23, 1917.

Application filed September 12, 1916. Serial No. 119,958.

To all whom it may concern:

Be it known that I, GEORGE A. MOORE, a citizen of the United States, and a resident of Medford, in the county of Middlesex and 5 Commonwealth of Massachusetts, have invented certain new and useful Improvements in Embroidery-Hoops, of which the following is a full, clear, and exact specification.

10 The purpose of this invention is the construction of improved means for tightening the ends of the hoop about the embroidery frame and the work between, in order to hold the latter snugly in place.

15 In a previous patent granted to me, No. 1,118,213, I set forth a device for the purpose comprising a cup-shaped thimble having a threaded opening in its bottom into which is screwed one of the hoop-members, 20 while the other hoop-member had a head about which the edges of the cup-shaped thimble were loosely forced to hold it against withdrawal. Notwithstanding the excellencies of the same, I have found it in 25 practice to be somewhat expensive to manufacture.

To reduce the expense to the minimum, I form an internal flange in one end of a tubular thimble, and thread the remainder 30 of its interior. The headed hoop-member is then inserted small end first from the threaded end of the thimble, and given a bend to prevent its accidental falling out; and the other hoop-member which has had 35 its end swaged to a larger diameter and threaded to fit the internal threads of the thimble, has such threaded end screwed into the thimble.

In the drawings forming part of this 40 specification, Figure 1 is a view on a reduced scale of an embroidery hoop provided with my improved tightening device. Fig. 2 is a longitudinal section on a larger scale of the thimble. Fig. 3 is a similar sectional view but showing the hoop-members engaged therewith. Fig. 4 is a side view of the headed hoop-member. Fig. 5 is a side view of the hoop-member having an enlarged threaded head. Fig. 6 is an end view 50 of the thimble.

As shown in Fig. 2, the thimble 1 is a substantially thin walled tube having an internal flange 2 at one end to form a comparatively small hole 3, and having the interior formed with screw threads 4. While

it is less expensive, so far as material is concerned, to form the thimble from tubing, with the flange 2 spun inward therefrom, I find that it is more economical in labor to make the same from either solid rod 60 metal,—preferably brass,—or from heavy tubing whose bore is about equal to the size of the hole 3. This rod, or heavy tubing, being fed to a turret lathe or automatic screw machine, its interior is first drilled 65 and reamed out to the form illustrated, the interior tapped, and then the thimble section separated from the remainder of the rod or tubing by the cut-off tool.

The exterior of the thimble should, however, be knurled as shown in Fig. 1 before it is thus cut off.

A slight head 5 is formed on the hoop-member 6, preferably by upsetting the metal thereat, and suitable rivet holes made 75 through it for the reception of rivets 7 by which it is to be fastened to the hoop 9, after which it is inserted in the thimble and through the hole 3 until its head 5 is stopped by the flange or shoulder 2. It is then given 80 the double bend 10 shown in Figs. 1 and 3, and attached to said hoop by the rivets.

The hoop-member 11 has upset thereon a large head 12 of a diameter to have its threads 13 properly screw within the threads 85 4 of the thimble, and it is also given a double bend 15 like that already shown at 10, and suitably fastened to the other end of the loop 9, as by rivets 16. By rotating the thimble, the hoop is tightened or loosened as desired.

What I claim is:

An embroidery hoop comprising a hoop-member, a wire attached to the hoop-member at one end and having its other end enlarged and threaded, a wire having one end formed with a head larger than the diameter of the wire but smaller than the threaded enlargement of the first-named wire, the other end of the second-named wire being 100 attached to an end of the hoop-member opposite to that to which the first-named wire is attached, and a section of tubing having one end internally flanged and the remainder of its interior screw threaded to co- 105 operate with said threaded enlargement.

In testimony that I claim the foregoing invention, I have hereunto set my hand this 12th day of September, 1916.

GEORGE A. MOORE.
